UNITED STATES PATENT OFFICE

ARTHUR W. OJERHOLM, OF WORCESTER, MASSACHUSETTS.

REED.

1,214,948.

Specification of Letters Patent.

Patented Feb. 6, 1917.

Application filed February 20, 1915. Serial No. 9,562.

To all whom it may concern:

Be it known that I, ARTHUR W. OJERHOLM, a citizen of the United States, residing at Worcester, in the county of Worcester and State of Massachusetts, have invented a new and useful Improvement in Reeds, of which the following is a specification.

This invention relates to reeds and more particularly to reed dents, constructed in such a manner as to be independently removed, and to form the spaces required between the dents in the reed.

This reed may be used as a loom-reed, warping-reed, or in any location necessary in the textile art. The object of my invention is to provide a reed whereby the upper or lower bearing, in which the dents are secured, may be readily removed to allow the threads to be inserted between the dents; also to allow the removal of one or more of the dents should they become bent, or for any other reason.

Another object of my invention is to provide a reed constructed in such a manner as to allow the dents to be changed to different widths of spacing as desired. With these and other objects in view, my invention consists in certain devices, combinations and arrangements of parts as will be hereinafter described and more specifically pointed out in the appended claims.

In the accompanying drawing, I have shown my invention sufficient to enable those skilled in the art to understand the construction and the operation thereon.

Referring to the drawing,

Figure 1 is a front view of the loom-reed containing my improved reed dent. Fig. 2 is a section on line 2-2 Fig. 1, looking in the direction of arrow "a," same figure.

Fig. 3 is a section corresponding to Fig. 2 but shows the top retainer partially removed.

Fig. 4 is a front view of an end portion of the reed with the top retainer removed.

Fig. 5 is a detailed side view of the reed dent shown in the above mentioned figures and looking in the direction of arrow "b" Fig. 3.

Fig. 6 is a front view of a modified form of my reed dent.

Fig. 7 is a side view of the reed dent shown at Fig. 6 looking in the direction of arrow "c" same figure.

Figs. 8 and 9 are detailed front and side views respectively of one form of spacer used in my improved dent.

Referring to the drawing, 60
10 and 11 are upper and lower retainers of semi-circular construction and have secured in their ends lugs, 12 and 13, having a tapped hole therein to receive screws, 14 and 15 as shown at the left of Fig. 1.

These screws 14 and 15 may be used in one or both ends of my improved reed.

16 and 16^a are end bars having their upper and lower portions mounted in the retainers, 10 and 11 and act to hold the retainers at an equal distance. 70

Mounted in said retainers 10 and 11 are the dents 17, formed of any suitable material and having lateral projections 17^a and 17^b.

The lower portion of said dents 17 are retained in their respective positions by spacers 18, inserted between each of the dents 17. 75

The flanges 17^a and 17^b retain the upper 80 portion of said dents 17 in spaced relation to one another.

19 is a modified construction of my reed dent and has lateral projections, 19^a and 19^b, at the upper portion thereof, the lower 85 portion is also provided with lateral projections 19^c and 19^d; the projections 19^a, 19^b, 19^c and 19^d acting as spacers between the dents when used in my improved reed.

The upper and lower portions of my reed 90 dents and the end bars 16 and 16^a, are preferably of irregular shape to allow said end bars and dents to be removed from the semi-circular retainers, 10 and 11.

I will now briefly describe the method of 95 removing one or more of the dents 17, and also the method used for inserting the threads between said dents:—

When one or more of the dents 17 are to be removed, the upper or lower retainer is 100 partially revolved on either the upper or lower portions of the dents 17, which by means of the irregular shape of said upper or lower portions, of said dents, the semi-circular retainers may be readily removed. 105

It is preferable when removing one or more of the dents 17, to remove but one of the retainers, either the upper or lower; the particular dent or dents to be removed may then be turned until the irregular shape allows said dents to be removed from the other retainer. 110

When it is desired to have the threads inserted in the spaces between the reeds either the upper or lower retainer is removed. The one not removed will hold the end bars 5 16 and 16^a and dents 17 in their vertical upright position, by means of the screw 15 the dents and end bars are retained transversely in their vertical position.

The threads 20 to be inserted are then 10 passed independently between the reed dents 17 and are guided between the upper portions of said dents 17, by means of the contour of the lateral projections thereon.

Having thus described my invention, it 15 will be evident that many changes and modifications may be made therein by one skilled in the art; and I do not wish to be limited to the specific details herein disclosed; but what I claim is:—

20 1. In a reed, a series of reed dents having irregular enlarged upper and lower ends, said enlarged ends being mounted within semi-circular retainers, said dents being independently removable by partially rotating 25 said retainers on said enlarged ends.

2. In a reed, a series of reed dents having irregular enlarged upper and lower ends, said enlarged ends being mounted within semi-circular retainers, said dents being independently removable by a partial rotation 30

of said retainers on said enlarged ends, spaces between said dents.

3. In a reed, a series of reed dents having irregular enlarged upper and lower ends, 35 said enlarged ends being mounted within semi-circular retainers, said dents being independently removable by a partial rotation of said retainers on said enlarged ends, said enlarged ends having lateral projections forming the required spaces between said 40 dents.

4. In a reed, a series of reed dents having irregular enlarged upper and lower ends, 45 said enlarged ends being mounted within semi-circular retainers, said dents being independently removable by a partial rotation of said retainers on said enlarged ends, said enlarged ends having lateral projections forming the required spaces between said dents, said projections being formed in such 50 a manner as to act to guide a thread in said dents at either their upper or lower ends.

In testimony whereof I have hereunto set my hand, in the presence of two subscribing witnesses.

ARTHUR W. OJERHOLM.
